UNITED STATES PATENT OFFICE.

AUGUSTUS H. HOLCOMB, OF SEATTLE, WASHINGTON.

CHANGEABLE SIGN.

1,292,467.

Specification of Letters Patent. Patented Jan. 28, 1919.

Application filed January 3, 1918. Serial No. 210,225.

To all whom it may concern:

Be it known that I, AUGUSTUS H. HOLCOMB, citizen of the United States, residing at Seattle, in the county of King and State of Washington, have invented a certain new and useful Improvement in Changeable Signs, of which the following is a specification.

My invention relates to improvements in changeable signs, and the object of my invention is to provide a series of separate plates upon each of which plates shall be inscribed words or devices of a different advertising sign and all of which plates shall be associated with power driven mechanism within an inclosing case in such manner that said mechanism shall be adapted to operate automatically to move said plates repeatedly, one after another, to and from a position where the signs inscribed thereon shall be exposed, each for a desired length of time, to the public view through an opening in said inclosing case.

I accomplish this object by devices illustrated in the accompanying drawings wherein—

Figure 1 is a view in front elevation of an advertising sign embodying my invention;

Fig. 2 is a view of the same in side elevation;

Fig. 3 is a plan view of the same;

Fig. 4 is a view in front elevation of a detail of the same;

Fig. 5 is an enlarged fragmentary view of the same in vertical section on broken line 5, 5 of Fig. 6, with some of its parts removed the better to show some of its internal parts;

Fig. 6 is an enlarged view of the same in vertical mid-section on broken line 6, 6 of Fig. 1;

Fig. 7 is an enlarged fragmentary view in front elevation showing the relative positions of some parts of the same;

Fig. 8 is a fragmentary view in vertical mid-section of the same on broken line 6, 6 of Fig. 1, and

Fig. 9 is a fragmentary view on a reduced scale showing details of the same in front elevation.

Referring to the drawings, throughout which like reference numerals indicate like parts, a rectangular frame of an inclosing case consists of two vertical studs 10 and 11, which are united by a top rail 14 and

a bottom rail 15 to form a front portion of said frame, and two studs 12 and 13 which are united by a top rail 16 and a similar rail that is not shown, to form the rearward portion of said frame, said front and rearward portions thereof being united by top rails 17 and 18 and bottom rails 19 and 20.

Extending between the top rails 17 and 18, in a position about midway between the front portion and rearward portion of the frame, is a bar 21 of angle iron, and, in a like manner, extending between the bottom rails 19 and 20, is a similar bar 22 that is also disposed midway between the front and rearward portions of said frame.

Extending vertically between the bars 21 and 22, are two studs 23 and 24, of angle iron, which are spaced from each other and disposed at equal distances respectively from each of the ends of the bars 21 and 22.

Disposed in the front portion of the frame, to extend upwardly from the bottom thereof for a distance of about one third of the height of said frame, is a panel 25 which serves to support the front edge portion of a shelf 26 whose rearward edge portion is supported by a rail 27 that is fastened to the studs 23 and 24.

Extending upwardly from the rearward edge portion of the shelf 26 and releasably fastened to the studs 23 and 24, is a panel 28, which is provided with a rectangular opening 29 that extends through the upper portion thereof.

Extending between the rearward portion of the frame and the vertical studs 23 and 24 is a shelf 30, which is disposed in a plane slightly lower than the plane of the shelf 26, and extending upwardly from said shelf 30 to the top of the frame are partitions 31 and 32, only the partition 32 of which has some of its rearward edge portion cut away, as indicated in Fig. 2, to form an opening into the space between said partitions 31 and 32.

Extending upwardly from the shelf 30 in a position spaced from the rearward portion of the frame is a sheet metal plate 33 which is provided with a circular opening 34, whose circular edge is indicated by the circular line 34 in Figs. 5 and 7, the lower portion of said plate 33 being curved toward the front portion of the frame.

Fastened to the rearward side of the rearward portion of the frame is a verti-

cally disposed back board 35 which extends from the bottom to the top of said rearward portion of the frame, but which is of a width that is less than the diameter of 5 the opening 34 of the plate 33.

Fixed in the back board 35 in a position concentric with the opening 34 is an inwardly projecting stud 36 upon which is rotatably mounted a wooden disk 37 whose 10 periphery is provided with a groove 38.

The front side of the outer circular edge portion of the disk 37 is reduced in diameter in order to permit the front portion of said disk freely to project through the circular 15 opening 34 of the plate 33, and said outer circular edge portion is provided with a plurality of pins 39 which are disposed at equi-distant points in a circular line to project through said circular opening 34 at 20 points adjacent to the edges of said opening 34.

Rotatably mounted in the plate 33, in a vertical line radiating from the axis of the disk 37, is a spindle 40 that projects horizontally to a point near the inner side surface of the panel 28, said spindle 40 being provided with an integral collar 41, of comparatively large diameter, which engages with the front side surface of the plate 33, 30 and with a rigidly attached toothed wheel 42, a side of which engages with the rear side surface of said plate 33, as more clearly shown in Fig. 8, which collar 41 and wheel 42 present large area of bearing surfaces 35 against the sides of said plate 33, thus to adapt the spindle 40 to sustain a considerable weight to which it may be subjected.

The axis of the spindle 40 is so disposed that the teeth of the toothed wheel 42 will 40 operatively engage, one after another, with the pins 39 in response to a rotation of the disk 37 thus to impart intermittent rotative movements to the spindle 40.

Rigidly disposed to extend through the 45 disk 37 at a point in the same radial line with one of the pins 39, and at a slight distance therefrom, is a tubular socket 43 within which is operatively disposed a slidably movable carrier stud 44 whose front end 50 portion is smaller than its rearward end portion, and whose front end portion is surrounded by a helical compression spring 45 which tends to force said carrier stud 44 toward its most rearward position to cause 55 the rearward end surface of said carrier stud 44 to engage with the adjacent surface of the back board 35 in which position the front end portion of said stud 44 will project forward beyond the plane of the front surface 60 of the plate 33.

As shown more clearly in Fig. 9, the left hand edge portion of the back board 35 is provided with a curved slot 46 which extends through it from its front side to its rear side, 65 and which is disposed in the path of the rear-

ward end portion of the stud 44 so that, in response to a rotation of the disk 37 in a contra-clockwise direction, when said stud 44 reaches said slot 46 the spring 45 will be permitted to force said stud 44 to move to 70 project its rearward end portion into said slot 46 while its front end portion will be withdrawn to a point rearward of the vertical plane of the front surface of the plate 33.

The left hand edge portion of the back 75 board 35, at a point below the slot 46 and in the path of the rearward end portion of the stud 44 is also provided with a curved slotted groove 47 that forms an inclined plane that extends from a point near the rearward corner edge of said back board 35 to a point on the front surface thereof that is distant from the front corner edge thereof, which inclined plane serves as a cam 80 which will engage with the rearward end 85 surface of the stud 44 to force said stud 44 forward, in response to a contra-clockwise rotation of the disk 37, again to project its front end portion forward to a point beyond the vertical plane of the front surface of the 90 plate 33 where it will remain during its travel upwardly through the right hand semi-circular portion of its path.

In Fig. 4 is shown a card receptacle formed of a rectangular piece 48 of sheet 95 metal, the end edge portions 49 and 50 and the bottom edge portion 51 of which are folded over to form a card holder within which is removably disposed a card 52 upon which may be printed any desired advertising sign.

Fastened to the central part of the upper edge portion of the sheet metal piece 48 is a metal tab 53 which is provided with two integral suspender hooks 54 and 55 disposed 100 one above the other, as shown more clearly in Fig. 4.

In the compartment beneath the horizontal shelf 30 is a grooved pulley 56 which is fixed on a shaft 57 which, in a manner not 110 shown, may extend to and connect with a source of rotary motion, as an electric motor, that may be disposed within the compartment under the shelf 26.

The top and opposite vertical sides of the 115 rectangular iron frame may be closed by suitable cabinet work not shown.

Operatively disposed in a groove 58 of the pulley 56 to extend therefrom to the groove 38, around the disk 37, is a belt, not 120 shown, whereby a rotation of the shaft 57 will cause a rotation of the disk 37 in an obvious manner.

In utilizing a changeable sign embodying my invention, as illustrated in the drawings 125 and as hereinbefore described, the structure is conspicuously disposed, as, for instance, in a show window of a store, and, in order to attract the attention of the public, the shelf 26 is used for the purpose of placing there- 130

on a display of objects that are designed to excite the curiosity of people passing said show window.

The structure being thus disposed, a plurality of card receptacles (each containing a card 52 having a different advertisement printed thereon) are operatively suspended on the screw-threaded spindle 40 by their upper hooks 54 of their respective tabs 53, 5 the hook 54 of each being disposed in the groove between different ones of adjacent convolutions of the screw-thread of said spindle 40 as indicated by the fragmentary view in Fig. 8.

15 The frontward one only of the card receptacle is shown in Fig. 6 in its operative position to display its printed card through the rectangular opening 29.

The card receptacles being thus suspended 20 on the spindle 40, rotary motion is communicated to the disk 37 in an obvious manner, and in response to each revolution of said disk 37 the pins 39 will engage with the teeth of the toothed wheel 42 to rotate the 25 spindle 40 one revolution in a clockwise direction which will cause the frontwardmost one of said receptacles to fall off from the front end of the spindle 40, which card receptacle will drop downwardly first to engage with a deflecting plate 59 and then to fall on to the top of the shelf 30 there to rest with its tab 53 in engagement with the front surface of the disk 37 until the carrier stud 44 of the revolving disk 37 engages with the 30 lower hook 55 of said tab 53, thus to cause the carrier stud 44 to carry with it in its upward course said card receptacle to a point registering with the axis of the spindle 40 whereupon the upper hook 54 of said tab 53 35 will fall into the rearwardmost one of the grooves between adjacent ones of the convolutions of the screw-thread of said spindle 40.

A continued rotary movement of the disk 37 will cause the rearward end of the carrier stud 44 to fall into the slot 46, thus 40 carrying its front end portion to move rearwardly to a point where it will not project from the front surface of said disk 37 until its said rearward end again engages with the inclined plane of the slot 47 when it 45 will again be moved forward to engage with the hook 55 of the tab 53 of the next succeeding card receptacle.

Obviously, each revolution of the disk 37 50 will rotate the spindle 40 one revolution with the result that each revolution of said spindle 40 will cause a card receptacle to drop from its front end thus to display through the opening 29 all of the advertisements of all the cards of the card receptacles successively, each for the length of time 55 that it takes for the disk 37 to make one revolution.

Manifestly, the spindle 40 may be adapted 60 by making it longer, to carry and sup-

port any desired larger number of card receptacles and the dimensions of the structure and its parts may be increased to display signs of any desired area.

The forms and arrangement of parts of my invention may be changed without departing from the spirit thereof.

What I claim is:

1. A changeable sign of the class described, which embodies a rectangular frame, 75 a back board fastened to the rearward side of said frame; a disk pivotally mounted on the inner side of said backboard and adapted to be rotated; a carrier stud slidably disposed to extend through said disk normally 80 to project its front end portion from the front side of said disk; a compression spring associated with said carrier stud and adapted to exert its force to move said carrier stud rearwardly to engage its rearward end 85 surface with the front surface of said back board; a slot formed in said back board and disposed in the path of the rearward end of said carrier stud at a point near the uppermost portion of said path, into which slot 90 the rearward end of said carrier stud may be projected in response to a rotation of said disk; a cam associated with said back board and disposed in the path of said carrier stud at a point in a lower portion of 95 said path, whereby said carrier stud may be moved to project from the front surface of said disk while it travels from said cam to said slot in response to a rotation of said disk; a metal plate provided with a circular 100 opening and fastened to said frame in a position parallel with and spaced from said back board with the circular edge of said opening adjacent to the front side surface of said disk; a plurality of pins disposed to project from the front side of said disk 105 at points equi-distant from each other in a circle concentric with said disk; a spindle rotatably mounted in said metal plate at a point adjacent to the edge of the circular opening thereof and in a vertical line radiating upwardly from the axis of said disk, said spindle being provided with a screw-threaded portion that projects forwardly from said metal plate and with a 110 spur wheel that is disposed rearwardly of said metal plate in a position to be engaged successively by said pins that project from the front side of said disk in response to 115 a rotation of said disk; a front board provided with an opening therethrough and fastened to said frame in a position spaced from and parallel with the front side of said metal plate; a plurality of sign card receptacles each provided with a suspension tab having two hooks disposed one above the other, said receptacles being disposed each with the upper hook of its tab in the groove between different adjacent convolutions of the screw-thread of said spindle to 120 125 130

be suspended therefrom, whereby one of said receptacles may disengage from said spindle in response to each revolution thereof to fall to a position where the lower hook of its tab may hook on to said carrier stud to be carried upwardly again to dispose its upper hook on the rearward portion of the screw-threaded portion of said spindle, whereby a different one of said receptacles will be exposed through the opening in said front board during the time of each revolution of said spindle; and means for communicating rotary motion to said disk.

2. A changeable sign of the class described, which embodies a frame; a back-board fastened to the rearward vertical side of said frame; a disk rotatably mounted on the inner side of said back-board; a plurality of pins disposed to project from the front side of said disk at equi-distant points of a concentric circular line thereof; a plate disposed above and adjacent to the edge of

the front surface of said disk; a spindle rotatably mounted on said plate and provided with a screw-threaded portion that projects forward from said plate and provided with a spur wheel that is fastened on its rearward end portion in a position to be operatively and successively engaged by said plurality of pins in response to a rotation of said disk thereby to rotate said spindle; a plurality of sign cards; and means associated with said disk and with each of said sign cards whereby said sign cards may be successively disposed to be suspended on the screw-threaded portion of said spindle to be moved forward thereon by the screw-thread to drop off the front end of said spindle in response to a rotation of said disk.

In witness whereof, I hereunto subscribe my name this 18th day of December, A. D. 1917.

AUGUSTUS H. HOLCOMB.
